UNITED STATES PATENT OFFICE.

ALLEN HARVEY WOODWARD, OF WOODWARD, ALABAMA.

LOCOMOTIVE WATERING APPARATUS.

Application filed May 31, 1928. Serial No. 281,920.

My invention relates to apparatus for supplying water to railway locomotives and has for its object the provision of apparatus of the character designated which shall be 5 movable longitudinally with respect to the locomotive and thus avoid the necessity of accurate spotting of the locomotive for the purpose of taking water.

A further object of my invention is to provide apparatus for watering locomotives, movable to various positions with respect to the locomotive and capable of delivering water to locomotives on either or both tracks of parallel railway tracks.

As is well known in the art to which my invention relates, modern railway trains, both passenger and freight, are of such length and weight that it is extremely difficult to stop locomotives, with the train attached thereto, accurately at a water crane so that water can be supplied to the locomotive, without serious shocks to the train. The difficulty is so great that it is almost the universal rule on railways for the train to be stopped short of the water crane and for the locomotive to be uncoupled from the train and spotted alone for taking water. This practice is objectionable for the reason that, when the locomotive is uncoupled from the train, leaks in the brake pipe cause the brakes on the train to set and it is necessary, when the locomotive is again coupled to the train, for the brakes to be pumped off and again tested before leaving, all of which occasions objectionable delays. It is accordingly very desirable that means be provided whereby water can be supplied to the locomotive when stopped with the train, within reasonable limits of space, thereby avoiding uncoupling 35 the locomotive from the train.

These and other difficulties are overcome by means of my invention and I provide watering apparatus wherein the supply means is movable longitudinally of the locomotive 45 for a substantial distance so that accurate spotting of the locomotive is obviated. Briefly, my invention comprises an elongated trough supported on tracks in an elevated position alongside the railway track and having spouts at both ends for delivery of the water into the locomotive tank. The trough is easily movable the full length of its supporting structure and means are provided for supplying water to the trough in all positions within the limits of its travel.

Apparatus embodying features of my in-

vention is illustrated in the accompanying drawings, forming a part of this application, wherein

Fig. 1 is a view in side elevation of the apparatus, and

Fig. 2 is a sectional view taken along the line II-II of Fig. 1.

Referring to the drawings, I show parallel railway tracks 10 and 11, midway between which are provided a plurality of upright intermediate structural frame members 12, and end frame members 13. All of the frame members are provided with side braces 14 disposed at an angle to the upright members. Supported on the tops of the intermediate members 12 and secured to the end members 13 in any suitable manner is a mono-rail 16. Extending longitudinally of the upright members and secured near the top thereof are opposed channels 17 and 18, the mono-rail 16 and channel rails 17 and 18 serving as a trough track for my improved apparatus.

At 21 is shown a trough, which is made of relatively light sheet metal and is provided on its underside with a plurality of flanged wheels 22 which ride on the mono-rail 16. Extending downwardly from the upper sides of the trough 21 and suitably secured thereto are opposed pairs of structural members 24 and 26 having wheels 27 and 28 journaled in their lower ends, which wheels ride in the channels 17 and 18 and prevent the trough 21 from tipping. The trough is freely movable, on the tracks thus provided, from end to end of the mono-rail 16 and, in all positions, between its limits of travel, is supplied with water from any convenient source of supply, as through a conduit 31 having a valve 32 interposed therein.

In order that the trough 21 may be readily moved to the desired position, I provide pull ropes 33 and 34 at the opposed ends thereof, which ropes run over sheaves 36 and 37 carried by the end members 13 and extend downwardly over the ends of the frame within ready reach of a man on the ground. Buffer springs 38 and 39 are carried by the members 13 to prevent damage to the trough 21 which might occur should it be banged against the end members 13.

At each end of the trough 21, in the lower portion thereof, is a T connection 41 and connected to each T connection are spouts 42 and 43 extending respectively over the tracks 10 and 11. The spouts 42 and 43 are connected to the T connection 41 by ball

joins 44 so that water can only run therefrom when a spout is lowered. In order that the spouts may be normally in a raised position, I provide counter-balance weights 46 attached to chains 47 which run over sheaves 48 and are secured to each of the spouts at 49. At 51 is shown, in dot and dash lines, a locomotive tender in position to receive water from the lowered spout 42. With all the other 10 spouts raised at that time, water only runs from the lowered spout.

From the foregoing description, the operation of apparatus made in accordance with my invention will be apparent. A locomotive 15 with its train is stopped at any convenient place within the limits of travel of the trough 21, and the trough is moved, by means of one of the pull ropes 33 or 34, to a position where one of the spouts 42 or 43 may be 20 lowered and entered in the man-hole of the locomotive tank. The valve 32 is then opened to supply water to the trough, whereupon it runs into the locomotive tank. The ball joints 44 provide some lateral flexibility for the 25 spouts so that the spouts may be entered to deliver water into the locomotive tender without accurate spotting of the trough 21.

From the foregoing description it will be apparent that I have devised an improved 30 watering apparatus for locomotives which is simple of construction and easy of operation and by means of which a locomotive may be stopped with its train within reasonable limits and the water supply apparatus moved 35 to a position to discharge water into the locomotive tender. It will be obvious that this apparatus may be duplicated to provide water for a number of locomotives at one time such as might be required with double-headers.

While I have shown my invention in but one form, it will be obvious to those skilled in the art that it is not so limited but is susceptible of various changes and modifications 40 without departing from the spirit thereof, and I desire therefore that only such limitations shall be placed thereupon as are imposed by the prior art, or as are specifically 45 set forth in the appended claims.

What I claim is:

50 1. In locomotive watering apparatus, the combination of a trough bodily movable longitudinally of the locomotive, a plurality of spouts carried by the trough and adapted to discharge into the locomotive tank, and means 55 for supplying the trough with water.

2. In locomotive watering apparatus, the combination of an elevated trough bodily movable longitudinally of the locomotive, a plurality of spouts carried by the trough and 60 adapted to discharge into the locomotive tank, and means for supplying the trough with water.

3. In locomotive watering apparatus, the combination of an elevated trough movable longitudinally of the locomotive, a plurality 65 of spaced spouts carried by the trough on both sides thereof and adapted to discharge into the locomotive tank, and means for supplying the trough with water.

4. In locomotive watering apparatus, the 70 combination of an elevated trough, supporting rollers for the trough to permit its movement longitudinally of the locomotive, a plurality of spaced discharge spouts mounted to be raised and lowered and carried by the 75 trough, each of said spouts being adapted to discharge into the locomotive tank when lowered, means for supplying the trough with water, and means for moving the trough to proper position for a spout to discharge into 80 the tank.

5. In locomotive watering apparatus for parallel railway tracks, the combination of a trough supported for longitudinal movement between the tracks and elevated higher 85 than the locomotive tank, spaced spouts on each side of the trough, a ball joint connecting each of the spouts to the trough and arranged to prevent the flow of water from the 90 spout except when it is lowered, and means for supplying the trough with water in all positions within its limits of movement.

6. In locomotive watering apparatus for parallel railway tracks, the combination of a trough supported for longitudinal movement between the tracks and elevated higher than the locomotive tank, spaced spouts on each side of the trough, a ball joint connecting each of the spouts to the trough and arranged to prevent the flow of water from a 100 spout except when it is lowered, counterbalanced means for normally holding the spouts in raised position, and means for supplying the trough with water in all positions within its limits of movement. 105

7. In locomotive watering apparatus for parallel railway tracks, the combination of a plurality of upright structural members arranged between the railway tracks, a trough track mounted on the upright frame members, a trough having wheels mounted on the trough track and adapted to be moved from end to end of said track, a pair of spouts at each end of the trough and extending outwardly towards the parallel tracks, a ball joint connecting each of the spouts to the trough and arranged to prevent the flow of water from the spout except when it is lowered, counterbalanced means for normally holding the spouts in raised position, and means for supplying the trough with water in all positions within its limits of travel. 115 120

In testimony whereof I affix my signature.
ALLEN HARVEY WOODWARD.
